GOLF PRACTICING DEVICE

Application filed November 9, 1927. Serial No. 232,060.

My invention relates to and has for a purpose the provision of a compact and durable device adapted to be used at any place where sufficient clearance exists to allow the free and unrestricted swing of a golf club, by which one can practice the striking of a golf ball with the club, the device supporting a golf ball for movement in response to striking of the ball with the club and functioning to return the ball to a definite position after being struck, so that the time and labor of retrieving and again properly positioning the ball after each stroke is obviated, to the end that one can, with the utmost ease and convenience obtain practice to keep in form and improve his game without the necessity of actually playing on the links.

A further purpose of my invention is the provision of a golf practicing device of the above described character with which an indicator is adapted to be associated, for indicating in terms of linear measurement the force or intensity of a blow struck the ball so that the golfer will be apprised of the length of the drive which would result from an identical stroke with the club on the links, the indicator capable of being instantly reset so as to be ready to register the result of the next stroke.

I will describe only one form of golf practicing device embodying my invention and will then point out the novel features in claims.

In the accompanying drawings,

Fig. 1 is a view showing in side elevation one form of golf practicing device embodying my invention;

Fig. 2 is a plan view of the device;

Fig. 3 is a vertical sectional view taken on the line 3—3 of Fig. 1 and looking in the direction of the arrows;

Fig. 4 is an enlarged horizontal sectional view taken on the line 4—4 of Fig. 1 and looking in the direction of the arrows;

Fig. 5 is an enlarged sectional view taken on the line 5—5 of Fig. 3 and illustrating the interior construction of the indicator embodied in my invention; and

Fig. 6 is a sectional view taken on the line

6—6 of Fig. 5 and looking in the direction of the arrows.

Referring specifically to the drawings in which similar reference characters designate similar parts in each of the several views, my invention in its present embodiment comprises a weighted metal base B of circular form provided on its underside with a pad 10 of rubber or the like and adapted to rest upon the floor, the base constituting a stationary support for a ball carrying element designated generally at E, and to this end the base is provided centrally with an upstanding ear 11 through a horizontal opening in which extends the threaded shank 12 of a thumb screw 13, the screw being threaded into a member in the form of a disk 14 and operating to clamp the disk to the ear 11. Threaded into the periphery of the disk is the reduced threaded end 15 of a stud 16 the stud having a head 17 in the form of an eye through which the finger or a suitable bar (not shown) is adapted to be extended to facilitate lifting of the device when moving it about.

The stud 16 constitutes a fixed axis upon which the ball carrying element E is adapted to be mounted for rotary movement.

The element E in the present instance comprises a head 18 having a vertical sleeve 19 through which the stud 16 extends, and a horizontal sleeve 20 extending radially from the sleeve 19 so as to support the head for rotary movement and into which one end of a rod 21 is adapted to be inserted and clamped by means of a set screw 22, the rod having a head 23 on its other end and constituting an arm for supporting a conventional golf ball G through which an opening 23* has previously been drilled diametrical- 90 ly to snugly receive the rod.

In applying the ball to the rod the latter is first removed from the sleeve 20 and the ball then slipped on the rod until engaged with the head 23 after which the rod is replaced and clamped in the sleeve, this construction permitting the ball to be readily removed when unfit for further use and a new ball substituted.

A horizontal arm 24 is formed integral 100

with the sleeve 19 and extends radially from the latter at a point diametrically opposite to the sleeve 20, the arm 24 being provided at its outer end with a weight 25 which, with the arm, functions to balance the weight of the sleeve 20, rod 21 and the golf ball G.

The lower end of the sleeve 19 is reduced in diameter as indicated at 26, to receive a cam 27 having its peripheral surface preferably in substantially the shape of a heart, the cam being forced onto the sleeve so as to be fixed thereto for rotation therewith. The peripheral surface of the cam is engaged by a roller 28 broadly constituting a movable abutment and rotatably mounted on a pin 29 extending through the bifurcated end 30 of a plunger 31, the latter being mounted to reciprocate in a barrel 32, horizontally disposed and formed integral with the ear 11. The roller is constantly urged into engagement with the cam 27 by means of a coil spring 33 disposed in the barrel and interposed between the plunger and a plug 34 fitting in the end of the barrel and secured against displacement by means of a set screw 35. The barrel is slotted longitudinally at diametrically opposed points as indicated at 36, and the roller 28 extends into the slots so as to prevent rotation of the plunger in the barrel with consequent displacement of the roller with respect to the cam. The cam 27 and spring pressed roller 28 constitute means by which the ball carrying element E and hence the golf ball G are constantly urged to a predetermined position, and it will be clear that the roller, in acting against the peripheral surface of the cam at any point between the high point 37 or the low point 38 formed by the crotch 39 of the cam, will cause the latter, and hence the element E, to rotate in one direction or the other depending which side of the high point the roller is acting against, to the end that the cam will ultimately be brought to rest with the roller seated in the crotch 39, thus causing the golf ball G, after being struck a blow and rotated, to be returned to a definite position.

In the operation of the device it is placed upon the floor of a room or on any level surface and the element E adjusted with respect to the base by loosening the thumb screw 13 and rocking the element about the screw until the desired elevation of the ball G above the ground level or mat is obtained, after which the golfer addresses the ball with his club and swings the latter in the usual manner to strike the ball. Upon the intensity of the blow struck the ball, depends the number of revolutions imparted to the element E, and it will be clear also that unless the ball is struck squarely, the number of revolutions will be accordingly reduced. During rotation of the element E the spring pressed roller 28 constantly acts to arrest the movement, and when the

momentum of the element is insufficient to overcome the tension of the spring 33 and move the high point 37 of the cam 27 past the roller 28, the element will commence to oscillate and ultimately be brought to rest with the roller in the crotch 39 of the cam. 70

To indicate to the golfer, in terms of linear distance, the number of revolutions made by the ball G when struck, I provide an indicator comprising a casing 40 having 75 an L shaped extension 41 secured to the disk 14 by screws 42, so as to rigidly support the casing on the disk. At one side of the casing 40, in a bore 43 is mounted for reciprocating movement an actuator 44 in the 80 form of a rod projecting from one end of the casing and having a head 45 normally urged by a spring 46 to the position shown in Fig. 5 so as to be disposed in the path of movement of the cam 27. During each revolution of the cam 27 the actuator 44 will be moved in the direction of the arrow (Fig. 5) to cause a pawl 47 pivoted at 48 on the actuator and normally urged to the position shown in Fig. 5 by a spring 49, to engage one of the teeth of a ratchet 50 rotatably mounted on a stationary shaft 51, and rotate the ratchet wheel a distance of one tooth, against the tension of a torsional spring 52 fixed at one end to the wheel and at its other end to the shaft, the ratchet wheel being latched against retrograde movement by means of a spring pressed latch lever 53 pivoted at 54 in the casing and projecting exteriorly of the latter through a slot 55 90 for manual manipulation to release the ratchet wheel when desired. Rotatable on the shaft 51 and fixed to the ratchet wheel at one side thereof is a disk 56 having a single tooth 57, adapted to engage any one of a plurality of pins 58 arranged in a circular series and projecting from one side of a disk 58^a rotatably mounted on a shaft 59, to the end upon each revolution of the disk 56 the disk 58^a will be rotated a distance 100 equal to the spacing between adjacent pins 58. 105

To the top side of the disks 56 and 58^a are secured numeral bearing dials 60 and 61 respectively (Fig. 2), and the open top of the casing 40 is closed by a cover plate 62 having openings 63 through which a single numeral on each of the dials can be viewed. The numerals of the dials are intended to represent linear distances, the numerals of the dial 60 representing yards and those of the dial 61 representing yards in hundreds, to the end that one complete revolution of the dial 60, which would be effected in response to ten revolutions of the element E 115 (there being ten teeth in the ratchet wheel 50), would indicate by the numeral 1 of the dial 61 a drive of one hundred yards. 120

After an actuation of the element E and the reading of the indications of the dials 130

60 and 61 the golfer can reset the dials to zero by pressing with his club against the projecting end of the latch lever 53 and releasing the ratchet wheel 50, thus allowing the spring 52 to restore the dials to zero position which is determined by the engagement of a stop pin 64 carried by the disk 58* with a second stop pin 65 fixed in the casing 40 as shown in Fig. 5.

10 Although I have herein shown and described only one form of golf practicing device embodying my invention, it is to be understood that various changes and modifications may be made therein without departing from the spirit of the invention and the spirit and scope of the appended claims.

I claim as my invention:

1. A device of the character described comprising a ball carrying element, means 20 for mounting the element for rotary movement in response to striking of the ball so as to cause the ball to travel in an orbital path, means on the element and means on the first means co-acting to urge the element to a predetermined position in which the ball occupies a definite position, whereby after the ball is struck it will be automatically returned to said definite position, said co-acting means comprising a substantially heart shaped cam, a roller, and means for urging the roller into engagement with the cam.

2. A device of the character described comprising means for supporting a golf ball, means for mounting the first means for rotary movement in one direction or the other about a fixed axis according as the ball is struck on one side or the opposite side so as to cause the ball to travel in an orbital path in one direction or the other, means on the first means and means on the second means co-acting to urge the first means to a predetermined position wherein the ball occupies a definite position, whereby after the ball is struck it will be automatically returned to said definite position, said co-acting means comprising a cam of substantially heart shape rotatable with the first means about the axis of the latter, a roller mounted on the second means for movement bodily, and means for urging the roller into engagement with the cam.

3. A golf practicing device comprising a support adapted to rest upon the floor, a ball carrying element mounted on the support 55 for rotary movement about a vertical axis, a cam fixed to said element for rotation therewith and having a peripheral cam surface of substantially heart shape, a plunger mounted for reciprocating movement on the support and having a roller, and means for constantly urging the roller into engagement with the peripheral surface of the cam for the purpose described.

4. A golf practicing device comprising a 65 support adapted to rest upon the floor, and

including a vertically disposed stud, a ball carrying element comprising a head rotatably mounted on the stud and having an arm on which the ball is adapted to be supported, a cam fixed to the head for rotation therewith, a roller, means for mounting the roller for bodily movement on the support, and means for constantly urging the roller into engagement with the cam.

5. A golf practicing device as embodied in 75 claim 4 wherein said head is provided with a sleeve receiving the stud, a second sleeve projecting angularly from the first sleeve, and said arm comprises a rod having one end removably fitted in the second sleeve and its other end provided with a head to retain a ball through which the arm is adapted to extend, against displacement from the rod, and means for securing the rod against displacement from its sleeve.

6. A golf practicing device comprising a support adapted to rest upon the floor, and including a vertically disposed stud, a ball carrying element comprising a head rotatably mounted on the stud and having an arm 90 on which the ball is adapted to be supported, a cam fixed to the head for rotation therewith about the stud and having a peripheral cam surface of substantially heart shape, a barrel secured to the support, a plunger reciprocable in the barrel having a roller rotatably mounted thereon, and a spring in the barrel engaging the plunger for urging the roller into engagement with the cam.

7. A golf practicing device as embodied in 100 claim 4 wherein the support comprises a base having an upstanding ear, a member to which the stud is rigidly secured, and a clamping screw extending transversely through the ear and member for clamping 105 the member to the ear, yet allowing rotational adjustment of the member about the axis of the screw.

8. A golf practicing device as embodied in 110 claim 4 wherein the support comprises a base having an upstanding ear, a member to which the stud is rigidly secured, and a clamping screw extending transversely through the ear and member for clamping the member to the ear, yet allowing rotational adjustment of the member about the axis of the screw, said means for mounting the roller comprising a barrel on the member, a plunger reciprocable in the barrel and on which the roller is rotatably mounted, said 115 urging means comprising a spring in the barrel engaging the plunger.

9. A golf practicing device as embodied in 120 claim 4 wherein an indicator is associated with the device and comprises a rotatable dial, and means operatively associated with the dial and operable by the cam to impart rotational movement to the dial in response to rotation of the cam.

10. A golf practicing device as embodied in 125

claim 4 wherein an indicator is associated with the device and comprises a rotatable dial, means for urging the dial to rotate in one direction, an actuator mounted for movement and normally urged to one position wherein it is disposed in the path of the movement of the cam so as to be actuated by the latter, ratchet and pawl means operatively associated with the dial and actuator and operable by the latter when moved by the cam to impart a predetermined amount of movement to said dial in a direction opposed to its urged direction, and releasable means for latching the dial against movement in its urged direction.

11. A device of the character described comprising means for supporting a golf ball, means for mounting the first means for rotary movement in one direction or the other according as the ball is struck on one side or the opposite side so as to cause the ball to travel in an orbital path in one direction or the other, an indicator including a dial, and means operable in response to rotation of the first means in one direction or the other to rotate the dial in one and the same direction comprising a cam rotatable with the first means, and an actuator engageable with the cam and operatively connected to the dial.

12. A device of the character described comprising means for supporting a golf ball, means for mounting the first means for rotary movement in response to striking of the ball, and an indicator for registering movement of the first means comprising a rotatable dial, means for urging the dial to rotate in one direction, an actuator mounted for movement, means operable in response to movement of the first means for operating the actuator, means operatively associated with the dial and actuator and operable by the latter, to rotate the dial in a direction opposed to its urged direction, and releasable means for latching the dial against movement in its urged direction.

13. A device of the character described comprising a ball carrying element, means for mounting the element for rotary movement in response to striking of the ball so as to cause the ball to travel in an orbital path, means on the element and means on the first means co-acting to urge the element to a predetermined position in which the ball occupies a definite position, whereby after the ball is struck it will be automatically returned to said definite position, said co-acting means comprising a substantially heart shaped cam, a movable abutment, and means for urging said abutment into engagement with the cam.

ANDREW C. VOLK.
